UNITED STATES PATENT OFFICE.

CARL WELLHÖFER, SR., OF HEIDINGSFELD, NEAR WÜRZBURG, GERMANY.

CASK-HEAD CLOSURE.

No. 805,508.

Specification of Letters Patent.

Patented Nov. 28, 1905.

Application filed February 25, 1905. Serial No. 247,394.

To all whom it may concern:

Be it known that I, CARL WELLHÖFER, Sr., a citizen of Germany, residing at Heidingsfeld, near Würzburg, Bavaria, Germany, have 5 invented certain new and useful Improvements in Cask-Head Closures; and I do hereby declare the following to be a full, clear, and exact description of the invention, such as will enable others skilled in the art to 10 which it appertains to make and use the same.

The present invention consists of an improved cask-head closure, as hereinafter set forth and particularly pointed out in the claims.

15 In order to render the present specification easily intelligible, reference is had to the accompanying drawings, in which similar letters of reference denote similar parts throughout the several views.

20 Figure 1 is a section through the head of a cask, showing the form of closure hitherto in use, the section being taken longitudinally of the closure-bar. Fig. 2 is a section taken at right angles to that of Fig. 1, showing the 25 damage to the head-staves liable with the kind of closure illustrated in Fig. 1. Fig. 3 is a section through the cask-head, showing one embodiment of the present invention, and Fig. 4 is a part plan view of Fig. 3. Fig. 30 5 is a part vertical section through the cask-head, showing a modified form of the invention. Fig. 6 is a plan view of the closure-bar and the feet for supporting the same. Fig. 7 is a part vertical section of a further modification, and Fig. 8 a plan of the bar. Fig. 9 shows a further embodiment in vertical section, and Fig. 10 an end view of Fig. 9.

In casks having the heads curved inwardly, as shown at Fig. 1, or otherwise not forming a 40 plane surface the lever-bar for tightening up the door *e* has usually been made as shown in Fig. 1, and consequently when the door is tightened up the stave of the head is liable to break away, as illustrated in Fig. 2, at the inclined portion close to the joint with the side-wall staves.

According to the present invention the feet against which the presser-bar works are so 50 connected to the latter that they will adjust themselves to the surface of the staves against which they press, and thus prevent the breakage of the latter at the point mentioned.

In the embodiment illustrated in Figs. 3

and 4 the door *e*, with its screw-spindle *e'* and 55 nut, is attached and tightened onto the cask-head by means of the cross-bar *a'*, pivoted at *c* to the feet *b*, which rest on the head-staves *t*. Owing to this arrangement the feet will accommodate themselves to the bend 60 of the staves, and breakage of the latter will be avoided.

In Figs. 5 and 6 the same result is attained by providing the feet *b'* with rounded heads, on which the ends of the presser-bar 65 *a* rest and against which they may be secured, by means of screw-studs *c'*, with nuts, so that in this case also the feet will accommodate themselves to the bend of the cask-head. The studs *c'* are arranged in corresponding slots of the bar *a*, as shown at Fig. 6.

In Figs. 7 and 8 the desired result is attained by curving the ends of the bar *a*, so that the studs *c* of the feet *b* will always be 75 at right angles to the latter whatever may be the curve of the cask-head.

As shown, the closure is suited to a cask-head of a definite curve. To adapt it for use changeably on different curvatures, the bar- 80 apertures might be elongated to form slots, as in Fig. 6.

In Figs. 9 and 10 the bar *a* is U-shaped in cross-section, and the feet *b* are pivoted between the webs of the same, as at *c*, the result being the same.

Obviously the invention is also available in securing bungs or closures in the curved sides of casks or in other positions where the wall does not form a level plane surface. 90

I claim as my invention—

1. The combination, with a cask and a closure therefor, of feet arranged to rest upon the cask at both sides of the opening, a bar spanning the opening and connecting the 95 feet, and means for attaching the closure to the bar at a point between the feet.

2. The combination, with a cask and a closure therefor, of feet arranged to rest upon the cask at both sides of the opening, a bar 100 spanning the opening and movably connected at its ends to the feet, and tension-applying means for attaching the closure to the bar at a point between the feet.

3. The combination, with a cask and a 105 closure therefor, of feet arranged to rest upon the cask at both sides of the opening, a bar spanning the opening and movably connect-

ed at its ends to the feet, a stud secured to the closure and passing through an aperture in the bar, and a nut threaded upon the end of the stud.

5 4. The combination, with a cask and a closure therefor, of feet arranged to rest upon the cask at both sides of the opening, an arched bar spanning the opening and pivotally connecting the feet, a stud secured to the closure and passing through a hole in the bar between the feet, and a nut threaded upon the end of the stud.

10 5. The combination, with a cask and a closure therefor, of feet having a broad bear-

ing-surface arranged to rest upon the cask at 15 both sides of the opening and ears extending upwardly, an arched bar spanning the opening and pivoted at its ends to the ears, a stud secured to the closure and passing through a hole in the bar between its two ends, and a 20 nut threaded upon the end of the stud.

In testimony whereof I hereunto affix my signature in the presence of two witnesses.

CARL WELLHÖFER, SENIOR.
